(57) **CLAIM**

The ornamental design for a medical robot, as shown and described.

DESCRIPTION

FIG. 1 is a front perspective view of a medical robot showing my new design.

FIG. 2 is a rear perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The features presented in broken lines represent unclaimed portions and surfaces of the medical robot and form no part of the claimed design.

1 Claim, 4 Drawing Sheets

FIG. 1

FIG. 2

FIG. 3

FIG. 4

FIG. 7

FIG. 8
